CLAIM

The ornamental design for a debridement tool, as shown and described.

DESCRIPTION

FIG. 1 is a perspective view of a debridement tool in accordance with our new design in an assembled configuration; FIG. 2 is a side elevation view of the design of FIG. 1 in the assembled configuration;

FIG. 3 is a top plan view of the design of FIG. 1 in the assembled configuration;

FIG. 4 is a bottom plan view of the design of FIG. 1 in the assembled configuration;

FIG. 5 is a perspective view of the design of FIG. 1 in a disassembled configuration;

FIG. 6 is a side elevation view of the design of FIG. 1 in the disassembled configuration;

FIG. 7 is a top plan view of the design of FIG. 1 in the disassembled configuration;

FIG. 8 is a bottom plan view of the design of FIG. 1 in the disassembled configuration; and,

FIG. 9 is a perspective, close-up view of the cutting head of the design of FIG. 1.

The broken lines represent portions of the design that form no part of the claim.

1 Claim, 5 Drawing Sheets
